BACK DRAFT VENT FOR RANGES

Jesse W. Barker, Geneva, N. Y.

Application February 10, 1933, Serial No. 189,844

6 Claims. (Cl. 126—36)

This invention relates to a damper or venting device for stoves or ranges and the like and more particularly combination ranges in which both gas and solid fuel is employed.

5 The principal object of the present invention is to provide a damper for stove oven and broiler compartments which is automatically operated by an attachment from a gas cock and wherein means is provided to prevent back pressure of 10 gases within the said oven or broiler compartment.

A further object is the provision of a damper adapted to be positioned within the smoke bag or hump at the rear of the stove and having 15 means associated therewith which will open with the damper to provide relief in the event of back draft.

These and other objects and advantages will be apparent as the specification is considered in 20 connection with the accompanying drawings, in which:

Figure 1 is a rear view of the damper frame and damper in assembled position partially within the smoke bag, with the damper in closed 25 position;

Figure 2 is an enlarged section on the line 2—2 of Figure 1;

Figure 3 is an enlarged rear view of the damper frame with the damper and damper door in open 30 position; and

Figure 4 is a section on the line 4—4 of Figure 2.

Referring more particularly to the drawings, wherein like reference characters designate similar parts throughout the several views, numeral 1 designates the rear wall of a combination range oven 2. The oven is heated in the conventional manner, either by products of combustion passing around it from a combustion chamber or 40 fire pot, not shown, or by the heat from a gas burner, not shown, located within or beneath the oven. The products of combustion from the fire pot, after circulating around the oven, pass beneath the oven and are discharged outwardly 45 through suitable openings, also not shown, into the lower end of a vertically arranged main discharge flue or smoke bag 3, of conventional construction, suitably secured to the rear wall of the range, whereby the flue gases are caused to pass 50 upwardly therethrough and thence into the atmosphere.

Vents or openings 4 are provided in the rear wall 1 of the oven, at the upper end thereof, for permitting the flue gases within the oven to escape 55 into the smoke bag 3. A substantially rectangu-

lar damper frame 5 is positioned within the smoke bag and is attached to the oven wall 1, approximately over the vents 4 therein, by means of screws or the like 5'. One end of the damper frame extends outwardly through a side wall 6 of the smoke bag, which extended end is provided with a bulged casing or housing portion 7, which vents into the room through an open outer end 8. The frame 5 is formed with a relatively narrow flange 9, extending around the periphery thereof, which is recessed or undercut at its inner end to provide a groove or channel 10. An inwardly extending flange 12, formed on the upper and lower edges of a substantially rectangular, relatively thin plate or damper 11, fits within the groove 10 and permits the damper to be slidably actuated within the frame, as hereinafter described. Openings 13 in the damper plate coincide with the oven discharge openings 4 for controlling the passage of oven gases or products of combustion from the oven directly to the smoke bag 3.

A frame 14 is positioned over the open end 8 of the damper frame casing portion 7 and is removably secured thereto by means of a nutted screw or bolt 15, which extends through a slotted lug 16 on the side of the casing. A flapper door 17 is pivotally attached to lugs 18 on the upper end of frame 14 by bolts or the like 19, whereby the casing opening 8 may be closed or opened, as will presently be described. The outer end of the damper plate 11 is reduced to form a handle 20 which slidably extends through a recess or cutout portion 21 in the frame 14. A lever 22 is pivotally connected at one end to a stud 23 on the end of the damper handle 20 and at its other end to a rack lever, not shown, which in turn is suitably connected to a gas cock, not shown, whereby rotation of the gas cock to "on" and "off" positions will actuate the slide damper in a well known manner, to open and closed positions respectively.

The damper handle 20 is provided with a lug or fin 24, adjacent its inner end, and a lug or fin 25 is also formed on the rear face of the door 17, to one side and adjacent the upper end thereof. The lugs 24 and 25 are so positioned that, when the gas is turned on to supply the oven burner, and upon the consequent outward sliding movement of the slide damper 11, the lug 24 is caused to abut the door lug 25 and thereby push the said door outwardly or ajar, to the open position shown in Figure 3 and in which position the openings 13 in the damper are in register with the vent openings 4 in the 55

rear wall of the oven, thus opening the damper. Upon a reverse movement of the damper the openings 4 and 13 will be out of register and the door 17 will be moved to closed position by gravity.

5 It will thus be seen that when the gas cock handle has been turned to "off" position, the slide damper 11, as shown in Figures 1 and 2, covers and closes the discharge openings 4 in the oven wall and the flapper door 17, at the outer end of 10 the damper casing 7, is closed to the atmosphere. Rotation of the gas cock handle to "on" position causes the damper plate 11 to be moved outwardly in which position, the damper openings 13 coincide with the discharge openings 4 in the oven wall and the flapper door 17 is moved to open or 15 ajar position, as shown in Figure 3.

When the slide damper and flapper door are in the open position described above, the flue gases generated by the gas burner within the oven are 20 permitted to pass outwardly through the damper openings into the main discharge flue or smoke bag from whence they pass upwardly to the atmosphere.

It is well known in the art that a back draft in 25 the smoke bag or oven results in the gases passing down the bag and back into the oven where they mingle with the gases within the oven and often cause an explosion. Circulation of necessary fresh air is also thus cut off from the burner. By 30 virtue of the present construction, the flapper door is in open position throughout the entire venting operation of the oven and therefore any back draft of flue gases will cause the downwardly travelling gases to pass laterally and outwardly 35 through the open flapper door into the atmosphere of the room instead of passing through the damper openings and back into the oven, with the aforementioned deleterious results.

Thus it will be seen that the operation of the 40 damper is entirely automatic and that in addition to venting the oven in an improved manner, an efficient and very satisfactory means for preventing back draft of gases within the oven is provided.

While a preferred embodiment of my damper 45 has been shown and described it is to be understood that various modifications in the design and construction may be made without departing from the scope and spirit of the appended claims. Should it be desired, the damper may also be operated 50 manually by disconnecting the lever 22 and gas cock connecting levers from the damper handle, in which case the slide damper may be moved to open and closed position by hand, or other means.

55 Having thus described my invention what I claim is:

1. In a dual range, a main discharge flue, a compartment having vents opening into said flue, a frame in said flue having a sliding damper

means movable therein for controlling said vents, a vent on one end of said frame communicating with the flue and the atmosphere for venting back flue gases, and pivoted means for closing said vent, and means for simultaneously actuating said pivot 5 means and said damper.

2. In a range, a main discharge flue, an oven having vents opening into said flue, a frame extending into and supported in said flue, a damper slidably positioned in said frame for controlling 10 said vents, and a vent on one end of said frame and means for closing said vent for venting back draft gases from said flue directly to the atmosphere, and means for simultaneously actuating said means and said damper.

3. In a range, a main discharge flue, an oven having vents opening into said flue, damper supporting means in said flue and extending through the wall of said flue, a damper slidably positioned in said supporting means and having a portion 20 thereof extending through the wall of said flue, a vent in the outer end of said damper supporting means communicating with the flue and with the atmosphere for venting back draft gases from the flue direct to the atmosphere and a pivoted door 25 member for opening and closing the vent, and means for simultaneously actuating said pivoted door and said damper.

4. In a range, a main discharge flue, an oven 30 having vents opening into said flue, a frame positioned in said flue and extending through one side thereof, a damper slidably positioned in said frame and having one end extending through the side of said flue, a vent on said frame in communication 35 at opposite ends with said flue and the atmosphere for venting back draft gases directly to the atmosphere, and a pivoted door member on the extended end of said frame for closing said vent, and means for simultaneously actuating said means and said 40 damper.

5. In a dual range, a discharge flue, an oven having vents opening into said flue, a damper for controlling said vents, a chamber communicating at one side with said flue, and having an opening 45 for venting into the room in which the stove is being operated, means for closing said opening and means for simultaneously actuating said first mentioned means and damper.

6. In a dual range, a discharge flue, an oven 50 having vents opening into said flue, a damper for controlling said vents, a back draft chamber communicating with said flue, said chamber having an opening venting directly into the room in which the range is being operated, a door for said opening operable by gravity to closed position, and means for simultaneously opening said door and 55 damper.

JESSE W. BARKER.
